CLAIM

The ornamental design for a container for a pacifier, as shown and described.

DESCRIPTION

FIG. 1 is a perspective view of a container for a pacifier of my design, shown in a partially opened position; FIG. 2 is a front elevation thereof with the container in a fully closed position, the rear view being a mirror image of FIG. 2;

FIG. 3 is a plan view thereof;

FIG. 4 is a perspective view of the container shown in an opened position;

FIG. 5 is a right-hand end view of the container;

FIG. 6 is a left-hand end view of the container;

FIG. 7 is an underside plan view of the container; and, FIG. 8 is a view corresponding with FIG. 2, but illustrating the opposite of the container.

FIG. 1

FIG. 2

FIG. 3

FIG. 4

FIG. 5

FIG. 6

FIG. 7

FIG. 8
